Inventor
Andrew Carson

United States Patent Office.

ANDREW CARSON, OF MEMPHIS, TENNESSEE.

Letters Patent No. 65,792, dated June 18, 1867.

IMPROVED FLOAT OR RAFT.

The Schedule referred to in these Letters Patent and making part of the same.

TO ALL WHOM IT MAY CONCERN:

Be it known that I, ANDREW CARSON, of the city of Memphis, in the county of Shelby, in the State of Tennessee, have invented certain new and useful Improvements in Floats for Saw-Mills, and for other purposes; and the following is a full, clear, and exact description of the same, reference being had to the accompanying drawings, making a part of this specification, in which—

Figure 1 represents a perspective view of my invention.

Figure 2 shows a section through the same.

The object of my invention is to construct a cheap, substantial, and durable foundation for floating saw-mills, movable wharves, or batteaux, for receiving and forwarding cotton and other kinds of freight, and for all purposes for which a secure foundation or float is needed.

My invention consists in securely fastening together a sufficient quantity of timber by pins or bolts, so as to form a solid mass, of any desired length, width, and depth to give sufficient buoyancy for the purposes for which it may be needed, and then placing cross-timbers on the top, on which to lay and secure the plank forming the platform or floor, longitudinal with the structure, leaving openings through crosswise, so that the waves or water, when agitated, may pass through freely; also, in placing on either side of the timber structure buoying floats to support and prevent the foundation from being rocked by the waves or surging billows and swells from passing steamboats, the buoying floats being attached in such a manner as to allow them to be detached and taken aboard when the structure is to be moved any considerable distance.

To enable others to construct and use my invention, I will describe it more fully, referring to the drawings, and to the letters marked thereon.

The base or foundation of the floating structure A A may be made of any light timber, from two-inch plank to large square timbers, they being alternately crossing each other at right and at various other angles, so that the mass, when secured together, is braced in every direction, so that it cannot easily be racked or stove to pieces. When a sufficient quantity of timber is fastened together to form the float A A, as above described, I place joists, a a a a, of sufficient width and thickness, across the whole top of the structure, leaving the spaces c c c c, between them, open on both sides for the water to flow through. To the top of the joists a a a the plank b b b b are fastened, which form the floor or platform on which to erect the saw-mill or receive and deliver freight.

The movable log bridges B B, which are hinged to one end of the float A A, show my improved mode of construction, and but little power is required to raise the logs out of the water on to the platform and to the saw-carriage, as the distance is but a few feet.

For the purpose of steadyng the structure when used for a saw-mill, and for making room to pile up and ship and deliver the sawed lumber, I construct buoys C C, and secure them to both sides of the float A A by a series of joists, d d d d, which may be of any desired length, they forming a sufficient platform for the sawed stuff, which is in a convenient place to be put on flatboats or delivered at wharves; the buoys C C and the joists d d d all being fastened in such a manner that they can be easily taken to pieces and taken on board the mill, which may be so provided with propellers that it can be moved from place to place by the same power that drives the saw-mill.

Thus it will be seen that a structure, as above described, for the purposes of a saw-mill, will possess many and great advantages over others, among which are, that it will be much more substantial than when on a boat, no possibility of it being crushed by ice or steamboats or of it being snagged or upset and sunk. As there will be no leaking, there will be no need of any pumps or apparatus for bailing out. The saw-mill operating so near the surface of the water, gives it a great advantage for handling both the logs and the sawed lumber, as also in delivering it.

A platform, constructed as above described, to be moved about from place to place in our lakes or rivers, will afford greater facilities for receiving cotton and other freight for shipment, where there are no permanent wharves, than by any other means yet devised.

Having thus fully described my invention, what I claim as new, and desire to secure by Letters Patent, is—

1. Constructing a float for saw-mills, or the purposes herein described, by securing a sufficient quantity of light timber or other material together in a solid mass, and supporting a platform on the same, substantially as herein described for the purposes set forth.

2. I claim attaching side floats to the main float, for steadyng the structure and making room to deposit the sawed lumber, as herein described.

ANDREW CARSON.
